US00D923499S

(12) **United States Design Patent** (10) **Patent No.:** **US D923,499 S**
Lee (45) **Date of Patent:** **** Jun. 29, 2021**

(54) **ON-BOARD DIAGNOSTIC DEVICE**

(71) Applicant: **MAKE GREAT SALES LIMITED**,
Wanchai (HK)

(72) Inventor: **Kin Choi Lee**, Wanchai (HK)

(73) Assignee: **MAKE GREAT SALES LIMITED**,
Hong Kong (HK)

(**) Term: **15 Years**

(21) Appl. No.: **29/714,023**

(22) Filed: **Nov. 20, 2019**

(51) LOC (13) Cl. **10-05**

(52) U.S. Cl.

USPC **D10/78; D10/75**

(58) **Field of Classification Search**

(57) **CLAIM**

The ornamental design for an on-board diagnostic device, as shown and described.

DESCRIPTION

FIG. 1 is a top isometric view of an on-board diagnostic device, in accordance with our design;

FIG. 2 is a bottom isometric view of the on-board diagnostic device of FIG. 1;

FIG. 3 is a right side view of the on-board diagnostic device of FIG. 1;

FIG. 4 is a left side view of the on-board diagnostic device of FIG. 1;

FIG. 5 is a front view of the on-board diagnostic device of FIG. 1;

FIG. 6 is a rear view of the on-board diagnostic device of FIG. 1;

FIG. 7 is a top view of the on-board diagnostic device of FIG. 1; and,

FIG. 8 is a bottom view of the on-board diagnostic device of FIG. 1.

(Continued)

The broken lines shown are included for the purpose of illustrating porting of the on-board diagnostic device that form no part of the claimed design.

1 Claim, 7 Drawing Sheets
